UNITED STATES PATENT OFFICE.

CHARLES H. MYERS, OF PHELPS, NEW YORK.

DESIGN FOR A THERMOMETER-BACK.

SPECIFICATION forming part of Design No. 16,141, dated June 30, 1885.

Application filed April 30, 1885. Term of patent 14 years.

To all whom it may concern:

Be it known that I, CHARLES H. MYERS, a citizen of the United States, residing at Phelps, in the county of Ontario and State of New York, have invented and produced a new and original Design for Thermometer-Backs; and I do hereby declare the following to be a full, clear, and exact description of the said design, such as will enable others skilled in the art to which it appertains to make and use the same, reference being had to the accompanying drawing, which forms part of this specification, and represents a front elevation of my new design for a thermometer-back, the leading features of which are a background or field having at the top a summer scene and a winter scene at the bottom, separated by a tablet adapted to have inscribed thereon any suitable words, characters, or figures.

The upper and lower boundaries of the tablet diverge from the representation of a thermometer, which crosses the tablet vertically, as shown.

I claim—

The design for a thermometer-back, consisting of a field having at its top a summer scene and at its bottom a winter scene, separated by a tablet, the upper and lower boundaries of which diverge from the representation of a thermometer crossing the tablet vertically, as shown and described.

In testimony whereof I affix my signature in presence of two witnesses.

CHARLES H. MYERS.

Witnesses:

JAMES J. JOHNSTON,
D. C. REINOHL.
